(57) **CLAIM**

The ornamental design for a vacuum bottle, as shown and described.

DESCRIPTION

1. Vacuum bottle

Figure 1.1 is a top orthographic view of a vacuum bottle showing the claimed design;

Figure 1.2 is a bottom rear orthographic view thereof;

Figure 1.3 is a front view thereof;

Figure 1.4 is a rear view thereof;

Figure 1.5 is a left side view thereof;

Figure 1.6 is a right side view thereof;

Figure 1.7 is a top plan view thereof; and

Figure 1.8 is a bottom plan view thereof.

1 Claim, 8 Drawing Sheets
